UNITED STATES PATENT OFFICE.

GEORGE GEER, OF PETERBOROUGH, NEW HAMPSHIRE.

KNIFE-SHARPENER.

SPECIFICATION forming part of Letters Patent No. 439,799, dated November 4, 1890.

Application filed April 6, 1886. Serial No. 197,942. (No model.)

To all whom it may concern:

Be it known that I, GEORGE GEER, a citizen of the United States, residing at Peterborough, in the county of Hillsborough, in the State of New Hampshire, have invented certain new and useful Improvements in Knife-Sharpeners, of which the following is a specification.

My invention relates to improvements in knife-sharpeners of the class which consist of two grooved or threaded rollers placed side by side and mounted upon a frame, so as to revolve freely.

The object of my invention is to simplify the construction and to improve the efficiency of the instrument, and also to arrange the cutting-rollers upon a stationary frame.

In the accompanying drawings all of the figures are made upon an enlarged scale.

Figure 1 is a side elevation of my knife-sharpener. Fig. 2 is a front elevation of the same, and Fig. 3 is a plan view.

A designates the frame having at one end a flange *a*, containing the screw-hole *b*, Fig. 2. I also provide the face of this flange with a little spur or spurs *c*. The other end of the frame *A* is provided with two rounded heads *d d*, with their faces offset a little, so as to lie in different planes, as shown most clearly in Fig. 2.

B B designate annular grooved rollers, which are mounted to turn loosely upon the headed shafts or rivets *g g*, by means of which rivets said rollers are secured to the heads of the frame. These rollers are of a peculiar form and resemble in side view ratchet-teeth—that is to say, one side of each ridge of the rolls is at right angles to its axis, while the other side of the ridge is at an oblique angle to the axis—thereby forming what might be termed a series of truncated cones placed one upon the other. These rollers are hardened, so as to make their cutting-edges lasting. The diameter of these rollers is a little greater than the distance between their axes, so that when they are placed in position the ridges of the rolls overlap each other, the rib of one roller lying in the groove of the companion roller, as shown in Fig. 2. The offset faces of the heads *d d* enable me to place the rollers in this position.

In use I make the frame *A* stationary by

securing it to the vertical side of some support—as, for instance, a window or door casting—at a convenient height for the operator—for instance, about shoulder high. The line 55 C in Fig. 1 indicates such a vertical face. In thus setting the sharpener in position that side of the grooves or ridges of the rollers which is at right angles to their axes should be placed uppermost, as shown.

To sharpen a knife the edge at the heel is placed between the rollers *b b* and the knife drawn downward lengthwise through the rollers, giving it more or less pressure according to the hardness or softness of the knife. By 65 mounting the cutting-rollers upon a stationary frame they are in a convenient position, always ready for use, and in use they will be less liable to cause the knife-blade to chatter or jar as it is drawn between them than is the 70 case when a similar instrument is held in the hand.

I am aware that prior patents show a knife-sharpener consisting, essentially, of a pair of screw-threaded rollers set side by side to 75 loosely revolve upon their axes in a frame on the end of a handle; also that another prior patent shows a pair of annularly-grooved rollers, the ridges and grooves of which are beveled alike upon both sides, said rollers being 80 mounted to loosely revolve within a frame, which frame is adapted to be slipped upon the tines of a fork in use. Another patent shows two disks beveled at their edges on one side only and set side by side with their 85 sharp edges directly opposite each other. All of said prior art is hereby disclaimed.

I claim as my invention—

1. The herein-described knife-sharpener, consisting of the frame *A*, having the base or flange *a* at one end for securing it in place and at the other end two rounded heads *d d* with their faces offset, so as to lie in different planes, and the two annular grooved rollers, each in the form of a series of truncated cones 95 placed one upon the other, said rollers being loosely mounted on their axes against the offset faces of the heads *d d*, and with their ridges overlapping each other, substantially as described, and for the purpose specified. 100

2. The herein-described knife-sharpener, consisting of a frame *A*, having the base or

flange *a* at one end for securing it in place and at the other end two rounded heads *d d*, and the two annular grooved rollers, each in the form of a series of truncated cones placed one upon the other, said rollers being loosely mounted on their axes with their ridges overlapping each other, substantially as described, and for the purpose specified.

3. In a knife-sharpener having a frame and pivoted roller provided with cutting-edges, a cutting-roller consisting of a solid piece of hardened metal having the form of a series of truncated cones placed one upon the other, the space between each cone-frustum forming an annular groove with a wall on one side at right angles to the axis of said roller and the wall on the opposite side at an inclined

angle thereto, substantially as described, and for the purpose specified.

4. In a knife-sharpener having a frame and pivoted rollers provided with cutting-edges, the herein-described frame *A*, consisting of a body portion, the base or flange *a* at one end for securing the frame in place, and the two rounded heads *d d* at the other end, the faces of said heads being offset and in different planes, whereby two like grooved rollers secured to said offset faces have their cutting-edges in different planes, as described.

GEORGE GEER.
